UNITED STATES PATENT OFFICE.

HENRY C. BAUSINGER, JR., AND HOWARD D. BARNES, OF BUCYRUS, OHIO.

SELVAGE ATTACHMENT FOR TEMPLES.

*Original application filed March 1, 1926, Serial No. 91,626. Divided and this application filed May 11, 1927. Serial No. 190,623.

This invention relates to a selvage attachment for temples, and has for its primary object a construction that is adaptable to various types of temples now on the market 5 and which, when arranged in position, will contact with the selvage of a web to assure a uniform width of the web and capable of controlling and directing the engagement of a cutting device with the thread to be cut.

10 An object of the invention is the novel construction of selvage device automatically operated in the movement of the laybeam so as to properly function with the selvage of a web and to periodically act to properly direct 15 the thread to be cut into operative engagement with the cutting device.

Another object of the invention is the design of a device that is adjustable so as to regulate the action of the device in the operation 20 of the temple and the web passing thereby.

Besides the above, our invention is distinguished in the combination and arrangement of parts that will readily accommodate 25 itself to lighter or heavier webs without in any way sacrificing the efficiency thereof.

With these and other objects in view, our invention will be better understood from a description of the same when taken in connection 30 with the accompanying drawing, wherein:—

Figure 1 is an elevation of the device attached to a loom;

Figure 2 is an end elevation;

35 Figure 3 is an end elevation looking in a direction opposite from Figure 2;

Figure 4 is a front elevation;

Figure 5 is a top plan view.

Again referring to the drawings illustrating 40 one of the many constructions of our invention, the numeral 1 designates in its entirety a temple construction which may be of the construction shown in our co-pending application filed March 1, 1926, Serial #91,626, the present application being a division of 45 that application.

Our improved selvage attachment consists 50 of an attaching plate 2 carrying the attaching bolts 3 whereby the plate may be rigidly and properly connected to the support of the temple with which the selvage fork is associated. A lever 4 is swingingly mounted

upon the pivot bolt 5 carried by the plate 2 and this lever has rigidly connected thereto the arm 6 or selvage fork proper terminating 55 in a pointed extremity 7 arranged in a predetermined position relative to the cutting knives 8 that form a component part of the temple structure. The arm 4 is constantly urged in a predetermined direction by the 60 spring 9, the extent of movement of which being controlled by the adjustable stop 10. This adjustable stop 10 curves toward the lever 4 and is provided with slots 11 associated with screws 12 carried by the plate 65 so that in the sliding movement of the stop the point of engagement between the stop and lever may be controlled for varying the swinging movement of the lever and thereby 70 the association of the pointed extremity 7 with the selvage of a web.

Referring to Figure 1, it will be noted that we arrange a roller 13 on the laybeam 14 so that in the swinging movement of the latter the roller will periodically engage the lever 4 75 for swinging the same in position against the action of the spring 9, thereby mechanically moving the pointed extremity 7 relative to the selvage and the thread that is to be cut by the knives 8. Thus the selvage fork performs the dual function of controlling and assuring the uniform width of the web and the proper directing of the thread into operative engagement with the knives.

From the foregoing description taken in 80 connection with the accompanying drawing, it will be appreciated that we provide a very substantial construction of selvage device that may be readily connected to temple structures 85 now on the market and which, when properly positioned relative to the selvage of the web, will engage the same to properly control the width of the web and the directing of a thread into operative engagement with the cutting device associated with the temple. 90 It will also be appreciated that the construction and positioning of the lever 4 is such that the same may be periodically struck in the movement of the laybeam so as to limit the operation of the device to such times as a change 95 of shuttle takes place so as to materially reduce the number of operations and thereby increase the life of the device as a whole.

It is, of course, to be understood that the de-

sign of the various parts may be changed and the parts associated in other relations than illustrated in the drawing and, therefore, we do not desire to be limited in any respect except as set forth in the appended claims.

We claim:—

1. In a loom, the combination with the lay, the breast beam, and the temple rolls thereon, of a selvage loop forming and retaining means comprising a lever pivotally mounted in upright position upon the breast beam, a weft-thread engaging point supported by the lever and projecting downwardly in proximity to the temple rolls, a spring connected with the lever and with the temple and yieldably holding the lever in active position, an abutment mounted upon the temple and having its upper end directed toward the lever and engageable by the portion of the lever above its pivot to limit the movement of the lever to active position, the abutment being adjustable to vary the elevation of its said end with respect to the pivot for the lever, and means upon the lay engageable with the upper portion of the lever to actuate the lever

to elevate the point in the movement of the lay toward the breast beam.

2. In a loom, the combination with the lay, the breast beam, and the temple rolls thereon of a selvage loop forming and retaining means comprising a lever pivotally mounted in upright position between its ends upon the breast beam, a weft-thread engaging point supported by the lever and projecting downwardly in proximity to the temple rolls, a spring connected with the lever below its pivot and with the temple and yieldably holding the lever in active position, and abutment arm slidably adjustably mounted opposite the lever upon the breast beam and having its upper end presented in position for engagement by the lever to limit the movement of the lever to active position, and means upon the lay engageable with the upper portion of the lever to actuate the lever to elevate the point in the movement of the lay toward the breast beam.

In testimony whereof we affix our signatures.

HENRY C. BAUSINGER, JR.
HOWARD D. BARNES.
